UNITED STATES PATENT OFFICE.

ERNST BLATTMANN, OF NONNENDAMM, NEAR BERLIN, GERMANY, ASSIGNOR TO
SIEMENS & HALSKE A. G., OF BERLIN, GERMANY, A CORPORATION OF GERMANY.

SPARKING PLUG FOR INTERNAL-COMBUSTION ENGINES.

1,105,746.

Specification of Letters Patent.

Patented Aug. 4, 1914.

Application filed January 17, 1913. Serial No. 742,598.

To all whom it may concern:

Be it known that I, ERNST BLATTMANN, a citizen of the German Empire, and residing at Nonnendamm, near Berlin, Germany, have invented certain new and useful Improvements in Sparking Plugs for Internal-Combustion Engines, of which the following is a specification.

My invention relates to that type of 10 sparking plug for internal combustion engines in which electric sparks pass between an outer casing and an electrode within it and so ignite the gaseous mixture. Such 15 sparking plugs are exposed to considerable wear and tear when in operation owing to high temperature, splashes of oil and so forth, hence they wear out very quickly and owing to such wear and tear often suddenly fail, causing serious irregularities in the 20 working of the internal combustion engine.

Experience has shown that when an electrode carrier composed of steel is put into use its exposed surface gradually undergoes a change, the important result of which is a 25 gradual increasing of the diameter of the electrode carrier. The casing of the spark plug is not affected by this action. In the class of spark plugs to which my invention relates, the electrodes are set at an angle 30 to the electrode carrier, the result being that the electrodes are forced outwardly by the swelling action referred to. Eventually 35 an electrode touches the casing and a short circuit is caused which prevents ignition. The 40 sparking plug is then shortcircuited and ignition no longer occurs. It is only the central steel pin, as far as it is uncovered, which is exposed to such destructive action. The casing, which is likewise of steel and from which the sparks directly pass, remains undamaged.

A primary object of my invention is to prolong the life of the sparking plug, and to this end I cover or coat the head of the central pin carrying the nickel electrode with

a nickel cap. Moreover I secure said cap in its place by means of the nickel pin which passes through the carrier. In this manner firstly there is obviated a premature destruction of the electrode carriers at their 50 ends inside the engine cylinder and secondly the nickel cap is firmly held by a part of the 55 sparking plug already existing, *i. e.* by the nickel pin, special fastening means, as rivets, being thus rendered unnecessary.

One illustrative embodiment of my invention is represented by way of example in the accompanying drawing, which gives a 60 sectional view of the improved sparking plug.

In this drawing, *S* is the central steel pin having the head *k* which serves as carrier for the pin-like electrode *s*.

w is the outer electrode and *i* the insulator.

n is the nickel cap which completely covers 65 the head of the electrode carrier and is secured in place by means of the nickel pin *s*.

I claim:

In a sparking plug for internal combustion engines, the combination of a plug casing, an insulator longitudinally mounted therein, an electrode carrier axially mounted in said insulator and comprising a head portion having a transverse bore and projecting from the insulator at the ignition end of 70 the plug and a shank attached to said head portion, a nickel cap completely covering said projecting head portion and having 75 holes registering with said bore, and a nickel pin fitting tightly in said holes and bore and set at its ends at the predetermined 80 85 sparking distance from said casing.

In testimony whereof, I have signed my name to this specification in the presence of two witnesses.

ERNST BLATTMANN.
